UNITED STATES PATENT OFFICE.

GEORGE W. LEWIS, OF GRINNELL, IOWA, ASSIGNOR TO GRINNELL WASHING MACHINE COMPANY, OF GRINNELL, IOWA, A CORPORATION.

GEARING DEVICE.

1,211,723.

Specification of Letters Patent. Patented Jan. 9, 1917.

Application filed November 6, 1912. Serial No. 729,897.

To all whom it may concern:

Be it known that I, GEORGE W. LEWIS, a citizen of the United States, residing at Grinnell, in the county of Poweshiek and 5 State of Iowa, have invented a certain new and useful Gearing Device, of which the following is a specification.

My invention relates to that class of gearing devices which are especially designed to 10 be used in connection with power driven washing machines and wringers therefor.

My object is to provide a device of this kind in which a number of tubs may be arranged on a single main support and then 15 the work of washing and wringing clothes may be carried on progressively from one tub to another and the wringing of clothes may be done from any one of the tubs into another regardless of whether or not the 20 washing mechanism is being operated.

More specifically it is my object to provide a single cover and dolly for use in connection with a number of tubs, and a single wringer with a reverse gear mechanism for 25 use in connection with a number of tubs, which wringer may be positioned to operate on the clothes that are being removed from the tub on which the cover is placed for the time being or from any of the other tubs, 30 whereby and by the use of a single dolly and a single wringer, the various steps in the process of washing and wringing clothes may be carried on by the operator without any shifting of the tubs upon the support.

My invention consists in certain details, in the construction, arrangement and combination of the various parts of the device, whereby the objects contemplated are attained, as hereinafter more fully set forth, 35 pointed out in my claims and illustrated in the accompanying drawings, in which:

Figure 1 shows a side elevation of a platform and gearing device for washing machines embodying my invention. Fig. 2 45 shows a top or plan view of said platform illustrating particularly the collapsible portion thereof. Fig. 3 shows another side elevation of said device, the dotted lines showing the cover in one position and the 50 full lines showing the cover in another position of its movement. Fig. 4 shows a detail, sectional view of part of the platform frame and one of the sliding bars whereby the collapsible portion thereof is mounted

on the main body of the frame. Fig. 5 55 shows a central, vertical, sectional view through the gear casing at the upper end of the central supporting post taken on the line 5—5 of Fig. 2, the wringer being shown at right angles to the position shown at Fig. 60 2, and Fig. 6 shows a sectional view through the gear casing for the wringer gears.

The main body of my improved platform comprises longitudinal frame members which are indicated in the accompanying 65 drawings by the reference numeral 10. Connecting the frame members 10 are the transverse frame members 11, and supporting the main body of the frame are legs 12 which are reinforced by braces 13. The frame 70 members may be made of angle iron or any other suitable material. The collapsible portion of my platform comprises a longitudinal member 15 and transverse bars or frame members 16 which are slidably mounted 75 in the frame members of the main body of the platform. The inner ends of the frame members 16 are preferably bent at right angles to the main portions thereof, as shown at 17 in Fig. 4, to prevent the entire withdrawal of the members 16 from the frame members of the main body of the platform. The member 15 is supported by legs 18. The leg 18 is connected with the adjacent leg 12 of the permanent portion of 80 the platform at each end thereof by means of links 19 and 20 which are pivoted together at their inner ends and pivoted to the legs 18 and 12 respectively at their outer 85 ends and are designed to fold upwardly 90 when the legs 18 are moved toward the legs 12. Each end of the member 15 is also connected to the permanent portion of the frame by a hinged joint comprising links 21 and 22 which are pivoted together and to 95 the member 15 and to the permanent portion of the platform respectively. The links 21 and 22 are arranged to collapse or fold in a horizontal plane and the links 19 and 20 are arranged to collapse in a vertical plane. It 100 will therefore be seen that the collapsible portion of the platform may be folded or collapsed thereby reducing the platform to approximately half its maximum size.

Supported on the permanent portion of 105 the platform is a motor 23. Rotatably mounted beneath the top of the permanent platform is a shaft 24, on the outer end of

which is a pulley 25 which is operatively connected with the motor by means of a belt 26. At the middle of the permanent portion of the platform and near the edge there- 5 of adjacent to the collapsible portion is an upright bearing or sleeve 27 in which is rotatably mounted a shaft 28. On the inner end of the shaft 24 is a beveled gear 29 and on the lower end of the shaft 28 is a beveled gear 30 in mesh with the beveled gear 29. At the upper end of the sleeve 27 is a collar comprising an internally screw-threaded sleeve 32 screwed upon the upper end of the sleeve 27 and having at its upper end an annular horizontal flange 31. At the outer edge of the flange 31 is an annular downwardly extending flange 33 provided with a plurality of openings 34^a, the purpose of which will be hereinafter more fully explained. Resting above the collar 31 is a cylinder 34 having on one side a downwardly extending flange 35. The cylinder 34 is designed to turn freely on the collar 30 about the shaft 28. Extending laterally from the cylinder 34 is a bracket 36 secured to which is a horizontal support or board 37. Slidably mounted beneath the board 37 is a rod 38, the outer end of which is preferably turned downwardly at 39. The inner end 20 of the rod 38 is designed to be received in the openings 34^a of the flange 33 in different positions of the rotation of the cylinder 34. For yieldingly holding the rod 38 at the inward position of its movement, I have fixed 25 on said rod a collar 40 and between the collar 40 and a downwardly extending flange or bearing 41 on the board 37, I have mounted an extensible coil spring 42. Fixed on the shaft 28 within the cylinder 34 is a horizontal beveled gear 43. A horizontal shaft 44 is rotatably mounted in a bearing formed in the wall of the cylinder 34 and is provided at its inner end with a vertical beveled gear 45 in mesh with the beveled gear 43 as 30 shown in Fig. 5. I provide a tub cover 46 which is hinged to the board 37 by means of a hinge 47 and is also pivotally mounted on the bearing 48^a of the shaft 44 by means of a hinge strap 48 and forms a support for the 35 dolly mechanism hereinafter mentioned. The outer end of the shaft 44 is operatively connected with a dolly shaft 49. The pivotal points 47 and 48 are in alinement with each other.

50 It will be seen that the tub cover 46 may be rotated on the shaft 28 as desired. Upon the permanent platform, I have mounted a tub body 50 which is hinged to the permanent platform by suitable hinges 51 to permit the tub to tilt for emptying the water therein. Any number of tub bodies may be placed upon the platform and the cover 46 55 may be turned about the shaft 28 to be used with any of the tub bodies. In Fig. 3, I have shown the tub 50 in full lines and have

shown a tub 52, with the dolly, and the operative mechanism therefor, in dotted lines.

Rotatably mounted on the shaft 28 and resting upon the central portion of the beveled gear 43 is a sleeve 53, at the upper end 70 of which is a horizontal annular flange 54, the outer edge of which rests upon the upper edge of the cylinder 34. The flange 54 is provided with a short downwardly extending flange 55 which is received within the 75 upper end of the cylinder 34 and serves to give said cylinder rigidity. Formed on the flange 54 and extending upwardly therefrom is a cylinder 56 provided with a detachable cover 57. It will be understood that the 80 cylinders 34 and 56 serve as gear casings and also as bearings for the various shafts herein described.

Mounted on the shaft 28 above the flange 54 within the cylinder 56 is a beveled gear 85 58. Formed on the cylinder 56 is a bracket 59 secured to which is a wringer 60. The shaft 61 of the lower wringer roll extends through the walls of the cylinder 56 which form bearings for said shaft. Slidably, but 90 non-rotatably mounted on the shaft 61 is a hub 62, formed on each end of which is a beveled gear 63. The gears 63 and 58 are so arranged that when the hub 62 is moved to different positions of its movement either 95 of the gears 63 may be held in mesh with the gear 58 or the gears 63 may be held in neutral position.

The hub 62 is operated by the following means: A lever 64 has one round end 64^a 100 which is pivoted off center to the casing 56 and extends to a point between the gears 63 adjacent to the hub 62 to permit the free rotation thereof but in such a manner as to control the sliding motion of said hub on the 105 shaft 61. The lever 64 extends through an opening 65 in the cover 57 and is pivoted at its outer end to a laterally extending rod 66, the other end of which rod 66 is pivoted to a lever 67, one end of which is pivoted to the 110 wringer 60 at 67^a. The lever 67 is of somewhat resilient material and is mounted adjacent to a sector 68 having a laterally extending flange provided with notches to receive a lug on the lever 67.

115 It will be understood that any suitable means for operating the hub 62 may be employed. In the upper end of the cylinder or gear casing 34, I have provided a plurality of openings 70.

120 Mounted in the frame of the wringer 60 is a slidable rod 71, one end of which is designed to be received in the openings 70 and which is held at the inward limit of its movement by an expansible coil spring 72.

125 It will be understood that the cylinder 56 may be rotated freely on the shaft 28 and the wringer 60 may be thereby swung to any suitable or desirable position.

130 In the practical use of my improved de-

vice, the cover 46 may be moved to position for use with the tub 50 or may be used on any other tub placed on the platform. The beveled gear 45 is always in mesh with the beveled gear 43 and the board 37 and the hinged cover 46 may be secured in the various positions of their movement around the center post by means of the sliding rod 38. The wringer 60 may be turned around 10 the center post to any desired position and may be secured in various positions of its movement by means of the sliding rod 71. The wringer may be rotated in either direction or may be held neutral by a manipulation 15 of the lever 67, whereby the hub 62 is controlled. The wringer 60 may be used over the tub 50 or over a basket 75, as shown in Fig. 1.

The advantages of my improved device, 20 in cases where a large amount of washing is done, may be seen from the foregoing description. The collapsible portion of the platform may be used or not. Additional 25 tubs or baskets may be placed upon the cross members 11 of the permanent platform or upon the cross bars 16 of the collapsible platform, and the size of the platform may be varied as desired. The tub 50 may be tilted for emptying and is always in position for use. The tub 50 may be used until 30 the clothes in it are washed and the cover 46 may then be swung over another tub and the dolly operated in the second tub, and the operator may, at the same time, wring the 35 clothes from the tub 50 into a basket supported upon the platform.

For the purpose of more clearly interpreting the claims, it may be explained that by the term "main support" as employed in the 40 claims, I refer to the frame on which the tubs are mounted. By the term "containers" as used in the claims, I mean tubs or their equivalents. By the term "first operating device" as employed in the claims, 45 I mean a dolly and its operating mechanism, or an equivalent thereof, and by the term "second operating device" as employed in the claims, I mean a wringer and its operating mechanism or an equivalent.

50 In the disclosures of this application, I have set forth a main support containing tubs arranged in a circle around a central point, but I do not desire to be understood as limiting myself to this arrangement.

55 I claim as my invention:

1. In a device of the class described, a tub, an upright support, a horizontal member rotatably mounted upon said support to swing in a horizontal plane, a cover hinged 60 to said horizontal member, an upright shaft in said cover, an agitator operatively connected therewith, and means for imparting

alternate rotary motion to said upright shaft.

2. In a device of the class described, a 65 frame, an upright thereon, a tub supported on said frame adjacent to said upright, a horizontal member mounted on said upright and adapted to swing in a horizontal plane, a cover hinged to said horizontal member, 70 an agitator supported by said cover, a gearing device on said upright, and means for operatively connecting said gearing device and said agitator.

3. In a device of the class described, an 75 upright, a tub adjacent thereto, a cover supported from said upright and adapted to swing in a horizontal plane from position over said tub to position away from the tub, an agitator supported by said cover, a 80 gearing device supported by said cover, a gearing device supported by said upright, and means for operatively connecting said gearing device with said agitator.

4. In a device of the class described, a 85 support adapted to receive a plurality of tubs, an upright member on said support, a horizontal member mounted thereon for rotation in a horizontal plane around the support, a cover member pivoted to said 90 horizontal member adapted to be moved to position above the tubs in various positions of said support, an agitator mounted in said cover member, a gearing device on said upright, and means for operatively connecting 95 said gearing device with said agitator.

5. In a device of the class described, a 100 tub, a support, a shaft rotatably mounted therein, a bevel pinion on said shaft, a horizontal flange upon said support having a cylindrical member provided with notches, 105 a cylindrical casing rotatably mounted upon said horizontal flange, said casing being provided with a horizontal bracket, a spring actuated latch in said bracket designed to engage the notch within the said flange to lock the said bracket against rotation, a horizontal member secured to said bracket, a cover hinged to said horizontal member, a 110 cover shaft in said cover, a dolly on said shaft, a pinion on said dolly shaft, a rack in mesh with said pinion, a horizontal crank shaft rotatably mounted on said horizontal member, a pinion on one end of said horizontal shaft designed to mesh with the pinion on said driving shaft to impart rotary motion thereto, a link connecting said crank and said rack to impart alternate rotary motion to said dolly shaft.

Des Moines, Iowa, Oct. 3, 1912.

GEORGE W. LEWIS.
